TOY

Sidney L. Long, Minneapolis, Minn.

Application April 24, 1944, Serial No. 532,520

13 Claims.

(Cl. 46—139)

My present invention relates to improvements in toys and, more particularly, to a mechanical action toy.

The main object of this invention is to provide novel means for imparting natural dancing movement to the figure of a loosely jointed inanimate person.

A further object of the invention is to impart variable lateral swaying movement to the dancing figure in addition to forward and backward movements.

Another object of the invention is to provide an inexpensive toy that can be disassembled simply by relative movement of certain parts of the toy and assembled in compact form for shipping.

Other objects of the invention will be apparent from the following description, reference being had to the drawing.

To the above end, generally stated, the invention consists of the novel devices and combination of devices hereinafter described and defined in the claims.

In the accompanying drawing, which illustrates the invention, like characters indicate like parts throughout the several views.

Referring to the drawing:

Fig. 1 is a side elevation of the improved toy;

Figs. 2 and 3 are views partly in elevation and partly in section taken on the lines 2—2 and 3—3 of Fig. 1, respectively; and

Fig. 4 is a view partly in side elevation and partly in section taken on the line 4—4 of Fig. 2.

The numeral 5 indicates a base on which is mounted a frame 6. This frame 6 comprising a pair of upright side members 7 is rigidly secured to a spacing block 8 which, in turn, is rigidly secured to the base 5.

A toothed wheel 9 is mounted between the frame side members 7. This wheel 9 comprises a pair of laterally spaced flat square members 10 secured at their centers to a spacing block 11. One of the wheel members 10 is turned about its axis relative to the other wheel member 10 to position its corners midway between the corners of said other wheel member. In this arrangement of the wheel member 7, their corners afford circumferentially spaced teeth 12 that are staggered. The wheel 9 is mounted on a shaft 13 that extends through aligned holes in the wheel members 10 and the spacing block 11. This shaft 13 is journaled in the frame side members 7. A hand crank 14 for turning the wheel 9 is secured to one of the end portions of the shaft 13.

It will be noted that one of the teeth of each wheel member 10 is cut off or flattened at 15 and these two teeth are circumferentially spaced from each other. The flattened surface 15 of the respective teeth 12 are different distances from the axis of the wheel 9, for a purpose that will hereinafter appear.

A lever 16 is intermediately fulcrumed on the upper end of a post 17 secured to the base 5. The upper end of the post 17 is rounded and extends into a concave seat 18 in the under side of the lever 16. Obviously, the rounded upper end of the post 17 and the seat 18 afford a ball and socket joint between the lever 16 and the post 17. A pivot pin 19 on the upper end of the post 17 loosely extends through a hole in the lever 16 and limits the movement of said lever on the post 17. The lever 16 is upwardly inclined from the frame 6 and its lower end portion extended between the frame side members 7 with working clearance. Said lever 16 extends under the wheel 9 and is held by one of its teeth 12. The upper face of the lever is flat and opposite longitudinal marginal portions thereof are successively engaged by alternate teeth 12 during rotation of the wheel 9. Said lever 16 at its upper end portion is much heavier than the lower end portion thereof and thereby yieldingly holds said lever at its lower end in engagement with the teeth 12.

In front of the upper end of the lever 16 is the figure of a loose-jointed inanimate person 20. The arms 21 of the figure 20 are pivoted thereto and said arms at their outer ends are rigidly secured at 22 to the respective end of the lever 16.

These arms 21, which are rigidly secured to the lever 16 on opposite sides thereof partake of like movement of said lever. This attachment of the figure 20 to the lever 16 imparts positive lateral swaying movement to said figure under the transverse rocking movement of the lever 16. But at the same time, the figure 20 is free to swing in the plane of the lever 16, on the pivots which connect the arm 21 to said figure.

As the circumferentially spaced staggered teeth 12 successively engage the lever 16, teeter action is imparted to said lever as well as transverse rocking movement. Obviously, the two teeth 12, having the flattened surfaces 15, impart different degrees of movement to the lever 16, both longitudinally and transversely, over that imparted thereto by the other teeth 12.

By reference to Figs. 2 and 3, it will be noted

that the frame 6 and the post 17 are offset from the transverse center of the base 5. This arrangement of the parts on the base 5 brings the hand crank 14, as well as the frame 6 and the post 17 between parallel planes at the longitudinal edges of the base 5 to facilitate the packing of the toy. To disassemble the toy, when packing the same, it is only necessary to lift the lever 16 from the pivot pin 19 and withdraw the lever 16 from between the side frame members 7.

It will be understood that the invention described is capable of various modifications within the scope of the invention herein disclosed and claimed.

What I claim is:

1. A toy of the class described, comprising an inanimate figure, a base, a frame and a post on the base, a member intermediately loosely pivoted on the post, said figure being attached to said member at one end thereof for relative pivotal movement and for common movement transversely of said pivotal movement, a shaft journaled on the frame, a pair of laterally spaced rectilinear members on the shaft, the corners of said pair of members affording teeth, the teeth on said pair of members being staggered for engaging the other end portion of the pivoted member on opposite sides of the pivot for pivotally moving the same and also for rocking the pivoted member transversely of its pivotal movement, and means for rotating the shaft.

2. In a toy of the class described, an inanimate figure, a support, a lever for imparting action to the figure, said lever being mounted on the support for compound pivotal and transverse rocking movements, a frame, a rotatable shaft on the frame having laterally and circumferentially spaced teeth operative on the lever for imparting said pivotal and rocking movements thereto, and means for rotating the shaft.

3. In a toy of the class described, an inanimate figure, a support, a lever for imparting action to the figure, said lever being mounted on the support for compound pivotal and transverse rocking movements, a frame, a rotatable shaft on the frame having laterally and circumferentially spaced teeth operative on the lever for imparting said pivotal and rocking movements thereto, the laterally spaced teeth being staggered, and means for rotating the shaft.

4. In a toy of the class described, an inanimate figure, a support, a lever for imparting action to the figure, said lever being mounted on the support for compound pivotal and transverse rocking movements, a frame, a rotatable shaft on the frame having laterally and circumferentially spaced teeth operative on the lever for imparting said pivotal and rocking movements thereto, certain of said teeth having different radii, and means for rotating the shaft.

5. In a toy of the class described, an inanimate figure, a support, a lever for imparting action to said figure, said lever being mounted on the support for compound pivotal and transverse rocking movements, a frame, a rotatable shaft on the frame having two laterally spaced series of circumferentially spaced teeth operative on the lever for imparting said pivotal and rocking movements thereto, and means for rotating the shaft.

6. In a toy of the class described, an inanimate figure, a support, a lever for imparting action to said figure, said lever being mounted on the support for compound pivotal and transverse rocking movements, a frame, a rotatable shaft

on the frame having two laterally spaced series of circumferentially spaced teeth operative on the lever for imparting said pivotal and rocking movements thereto, the two series of teeth being on opposite sides of the lever and staggered, the radii of one of the teeth in one of the series being different from the radii of the other teeth of the respective series, and means for rotating the shaft.

10 7. In a toy of the class described, an inanimate figure, a support, a lever for imparting action to said figure, said lever being mounted on the support for compound pivotal and transverse rocking movements, a frame, a rotatable shaft on the frame having two laterally spaced series of circumferentially spaced teeth operative on the lever for imparting said pivotal and transverse rocking movements thereto, the two series of teeth being on opposite sides of the lever and staggered, the radii of one of the teeth in each series being different from the radii of the other teeth of the two series, and means for rotating the shaft.

15 8. In a toy of the class described, an inanimate figure, a support, a lever for imparting action to said figure, said lever being mounted on the support for compound pivotal and transverse rocking movements, a frame, a rotatable shaft on the frame, a pair of laterally spaced rectilinear members on the shaft, the corners of said members affording teeth operative on the lever for imparting said pivotal and rocking movements thereto, the teeth of said members being staggered, and means for rotating the shaft.

30 9. In a toy of the class described, an inanimate figure, a support, a lever for imparting action to said figure, said lever being mounted on the support for compound pivotal and transverse rocking movements, a frame, a rotatable shaft on the frame, a pair of laterally spaced rectilinear members on the shaft, the corners of said members

affording teeth operative on the lever for imparting said pivotal and rocking movements thereto, the teeth of said members being staggered, and means for rotating the shaft.

35 10. In a toy of the class described, an inanimate figure, a support, a lever for imparting action to said figure, said lever being mounted on the support for compound pivotal and transverse rocking movements, a frame, a rotatable shaft on the frame, a pair of laterally spaced members on the shaft, the corners of said members affording teeth operative on the lever for imparting said pivotal and rocking movements thereto, the teeth of said members being staggered, the pointed portion of one of the teeth of each member being cut off, and means for rotating the shaft.

40 11. In a toy of the class described, an inanimate figure, a support, a lever for imparting action to said figure, said lever being intermediately mounted on the support for compound pivotal and transverse rocking movements, a frame, a rotatable shaft on the frame having laterally and circumferentially spaced teeth operative on the lever for imparting said pivotal and rocking movement thereto, one end portion of the lever

45 being attached to the figure and the other end portion thereof loosely extending under the teeth and yieldingly held to be contacted thereby, and means for rotating the shaft.

50 12. In a toy of the class described, a base, a frame and a post on the base, a member mounted

on the post for compound movement about a pivot consisting of a pivotal movement in a vertical plane and for rocking movement transversely of said plane, an inanimate figure, said member being operative on the figure to impart action thereto in said plane and transversely thereof, and driven means mounted on the frame, said member being yieldingly held relative to said member, said means being constructed and arranged to intermittently directly engage said member in succession at transversely spaced points to impart said pivotal and rocking movements thereto.

13. In a toy of the class described, a wheel having teeth that are circumferentially spaced and staggered transversely of the wheel, means for operating the wheel, an inanimate figure, a member for imparting action to the figure, said member being loosely fulcrumed for pivotal movement in the plane of the wheel and for rocking movement transversely thereof, said member being yieldingly held relative to the wheel, so that its teeth successively engage the member and impart said pivotal and rocking movements thereto.

SIDNEY L. LONG.
